UNITED STATES PATENT OFFICE

146,831

DESIGN FOR A COMBINED TIE, TROUSER,
AND JEWELRY HOLDERMurrey M. London, Venice, Calif., assignor to California Slack Rack Co., Venice, Calif.

Application February 5, 1946, Serial No. 126,278

Term of patent 3½ years

(Cl. D33—8)

To all whom it may concern:

Be it known that I, Murrey M. London, a citizen of the United States of America, residing in the city of Venice, in the county of Los Angeles, State of California, have invented a new, original, and ornamental Design for a Combined Tie, Trouser and Jewelry Holder, of which the following is a specification, reference being had to the accompanying drawings forming a part thereof.

Fig. 1 is a perspective view of a combined tie, trouser and jewelry holder showing my new design,

Fig. 2 is a top plan view of the combined tie, trouser and jewelry holder shown in Fig. 1, and

I claim:

The ornamental design for a combined tie, trouser and jewelry holder, substantially as shown.
MURREY M. LONDON.
